GERTRUDE F. WEDDERBURN, OF CHEVY CHASE, MARYLAND.

CARD-SUPPORT FOR DUMMY HANDS.

1,076,850.

Specification of Letters Patent.

Patented Oct. 28, 1913.

Application filed March 21, 1906. Serial No. 307,976.

To all whom it may concern:

Be it known that I, GERTRUDE F. WEDDERBURN, a citizen of the United States, residing at Chevy Chase, in the county of 5 Montgomery and State of Maryland, have invented certain new and useful Improvements in Card-Supports for Dummy Hands, of which the following is a specification.

My invention relates to game-boards, and 10 has for its objects to provide novel means for supporting "card-hands" or series of cards whereby two persons are enabled to play a four-handed game of cards, the series of cards comprising the auxiliary or 15 dummy hands being so held or supported that each of said dummy or auxiliary hands is clearly disclosed to the player thereof and at the same time and in the same position is effectively screened from observation or inspection by his opponent; to embody such 20 means in compact and portable form that it may serve as a receptacle for the pack or packs of cards and other accessories employed in the game.

25 My invention is particularly well adapted for the game of whist and likewise for "bridge-whist," as hereinafter disclosed and set forth.

30 My present invention comprises various structures relating to the wholly original idea set forth in my basic Patent No. 805,895.

35 Referring to the accompanying drawings, which form a part of this specification, and in which like parts are similarly designated throughout the several views, Figure 1 is a perspective view of one form of my invention. Fig. 2 is a perspective view of a modified form. Fig. 3 is a sectional view of a 40 structure similar to that shown in Fig. 1. Fig. 4 is a perspective view of a base of two separable sections. Fig. 5 is a similar view showing the sections separated.

45 My invention as shown in all the several modifications illustrated in the drawings consists in a base of any proper material having formed therein two substantially parallel grooves for receiving the lower ends of two hands or series of playing cards 50 and provided with a supporting surface extending upwardly from the grooves and inclined to the vertical for supporting, if needful, the backs of said cards, said supporting surface, however, may be dispensed with and the cards supported by being gripped at their lower portions in the

grooves. Each of said series of cards constitutes a hand when the device is employed by two players in playing games, such as "whist" or "bridge", in which the cards 55 are dealt in four sections or hands, and when so used the device is placed preferably diagonally between the players who sit adjacent each other, the cards being disposed in the grooves with the cards of the two 60 hands facing each other so that said hands are held in their proper sequence of play.

65 As shown in Fig. 1, my device comprises a rectangular block of any proper material, such as wood, metal, paper mâché, glass, 70 rubber, or composition, which has formed therein two substantially parallel grooves or slots 2, said grooves being formed near the longer edges of the block. Clamping strips 3—3 of spring metal are formed to fit one in 75 each of said grooves or slots 2, one end of each of said strips being continued upwardly to form an upstanding supporting surface for the back of the cards. The cards are placed so that their lower ends are 80 gripped by the strips 3, the tension of which may be varied as desired by withdrawing the same from the grooves 2 and bending with the fingers. As positioned the strips 3 would support the cards of the two hands 85 slantwise so that the cards in one hand would diverge upwardly relatively to the cards in the other hand, this position being the best when the cards are placed in the holder so that the cards of the two hands 90 face each other. If desired, however, the strips 3 may be withdrawn from the slots 2 and reversed therein whereupon the cards of the two hands would be supported convergingly so that their upper ends would be 95 nearer than their lower ends. The central portion of the block is hollowed out or recessed as at 4 to provide a space or recesses for holding the decks of cards and score cards, and any convenient means such as 100 clips 5 or the hinged lid 30 may be used to retain the cards in the recess. A hole 6 is also bored lengthwise at one end of the block 1 to receive a pencil.

105 In Fig. 2 the holder is shown of skeleton form, pressed, cast or otherwise formed of proper material. In such form the card holding grooves 22—22 are substantially the same as shown in the construction shown in Fig. 1, and the central recess 24 for holding 110 the pack of cards, etc., is formed by the pressed side walls 21.

In Figs. 4 and 5, the card holder comprises the separable sections 55 and 56, each section comprising a rectangular block having its upper portion cut to provide a broad 5 V-shaped recess, the sloping sides 57 and 58 of which form the upper face of the block, the card holding grooves or slots 59 being formed by a groove or cut continuing the slant of the face 57 and undercutting the 10 face 58. The cards are placed with their lower ends in the grooves or slots 59 and their backs resting on the face 57. The sections may be placed as shown in Fig. 4 or may be separated as shown in Fig. 5 to 15 bring each hand into any preferred position. When placed as in Fig. 4 the cards of the two hands are held face to face and diverging upwardly, but it is obvious that the sections may be reversed to bring the cards 20 of the two hands back to back converging upwardly.

The use of my double dummy card-holder in the game of bridge-whist greatly enhances the interest of the game by enabling 25 each player to play two hands continuously and to deal and make the trump twice instead of once in each round of dealing and, further, to pit his skill (unhampered by a partner) against a single adversary.

30 When the cards are arranged face to face in using my card-holder the two players do not sit opposite each other, but at adjacent sides of the table, placing the card-holder so that each player's dummy hand is 35 approximately opposite him, and therefore in proper sequence of play. The face to face arrangement of the cards is greatly preferred since in arranging the cards back to back confusion as to sequence of play is 40 created.

Having thus described my invention, I claim as new and desire to secure by Letters Patent—

1. A card game device for enabling two 45 players to play four handed card games, which comprises holders for two of the four card hands, each holder being provided with means adapted to engage the opposite sides

of the cards at the bottom thereof so spaced apart as to allow but a limited play of the 50 cards therein whereby the cards are maintained against accidental displacement.

2. A device for enabling two players to play four handed games such as whist, bridge, etc., provided with duplicate means 55 for engaging, each, the cards forming a hand, each of said means adapted to engage the opposite sides of the cards at the bottom thereof so spaced apart as to allow but a limited play of the cards, whereby the 60 cards are engaged at their lower ends only and are maintained against accidental displacement, said duplicate means being so disposed as to hold the two card hands slantwise and at an angle to the vertical. 65

3. A card game device for enabling two players to play four handed card games, which comprises a block having holding means for two of the four card hands, each holding means adapted to engage the opposite sides of the cards at the bottom thereof 70 so spaced apart as to allow but a limited play of the cards therein, whereby the cards are maintained against accidental displacement.

4. A card game device for enabling two players to play four handed games of cards, comprising duplicate holders, each holder being provided with slotted means adapted to engage the opposite sides of the cards at the bottom thereof so spaced apart as to allow but a limited play of the cards therein whereby the cards are maintained against accidental displacement, and each having a removable clip therein comprising an inclined support and each holder arranged to be positioned to support the series of cards forming the hand so that the same 85 will be fully displayed to the player of the complementary or partner hand and concealed from the player of the opposing hand.

GERTRUDE F. WEDDERBURN.
